UNITED STATES PATENT OFFICE.

EDWIN BRILLINGER, OF YORK, PENNSYLVANIA.

WOOD-GRAINING MACHINE.

SPECIFICATION forming part of Letters Patent No. 288,302, dated November 13, 1883.

Application filed May 15, 1883. (No model.)

To all whom it may concern:

Be it known that I, EDWIN BRILLINGER, a citizen of the United States, residing at York, in the county of York and State of Pennsylvania, have invented a new and useful Improvement in Wood-Graining Machines, of which the following is a specification.

This improvement relates to that class of machines in which a roller engraved in relief is made to impress its design upon the material run through the machine, the design-roller being suitably mounted and connected with pressure-rollers for that purpose.

The object of the invention is to produce a machine in its simplest form, and so arranging it that the product of the machine will be double of those which have preceded it.

This improvement is more particularly adapted to cigar-box manufacturers' use, a very correct imitation of expensive woods being obtained by the use of the apparatus.

The drawings herewith forming part of this specification fully disclose the nature of my improvements, like letters in which designate like parts in all of the same.

Figure 1 is a side elevation, showing the connecting-gears and feeding-tables. Fig. 2 is a front elevation, showing part of counter-shaft, driving-pulley, and driving-gear, the tables removed; Fig. 3, side elevation on the driving-gear side, the tables removed, in all of which A represents the side frames; A', central horizontal jaw for the reception of the design-roller-bearings boxes; A², upper vertical, and A³ lower vertical, jaws, for the bearing-boxes of the pressure-rollers; B, caps to the jaws; C, screws regulating the pressure upon the rolls; D, brackets for the feeding-tables; E, feeding-tables; F, pressure-rolls; G, design-roll; H, H, H, equal connecting gear-wheels; I, main driving-wheel; J, pinion for the same; K, counter-shaft; L, driving-pulley; M, pad-bearings for the counter-shaft; N, the driving-belt.

The construction of the machine is simple, the frames are each cast in one piece, the jaws are planed to size, and the bearing-boxes to fit. After placing the central design-roll in position, the upper pressure-roll is let down in the jaws and rests upon a thickness of rubber of about the thickness of the lumber to be

passed through the machine. The lower pressure-roll bearings rest upon the cap until the regulating-screws are operated, when they rest upon the same; and the roll is also brought up 55 toward the central design-roll until the space will just take the board to be grained between them. The rolls may all be of metal, or the design-roll of metal and the pressure-rolls of wood. The design-roller is first smoothly 60 turned and polished. It is then prepared to receive a transfer of the grain of the desired wood to be imitated. The transfer may be made directly from the wood or sketched on by hand. After the transfer has been made, 65 the spaces between the leading lines are with proper tools cut out, leaving the leading lines projecting from or in relief upon the surface of the roll.

The operation of the machine is as follows: 70 Having been adjusted as described, the lumber, previously planed to thickness, is placed convenient to the machine. Two operators are required, if the machine is to be worked to its full capacity, or if the lumber is to be grained 75 upon both faces. The lumber is first fed in from the rear table, between the design-roll and upper pressure-roll, is received by the operator at the front, dropped upon the lower table, and passes between the design-roll and 80 lower pressure-roll. In this case the lumber is grained upon both faces, the lower face being grained in its passage from the rear to the front, and the upper face in its passage from the front to the rear of the machine. For single-face graining, ungrained lumber would be placed at both front and rear of the machine, and each operator would insert an ungrained and remove a grained piece consecutively. I prefer to perform the operation of graining 85 before any coloring is applied to the wood, the coloring and polishing of the wood being subsequently performed in special machines for that purpose.

Wood-graining machines and rolls in themselves are not new, and are fully described in several patents, specifically in No. 238,181, February 22, 1881, E. Struppe, wood-graining machinery, in which the graining-roller is composed of a series of alternating disk-cutters and washers secured upon a spindle by lock-nuts, and provided with a single

pressure-roll, which may be placed indifferently above or below the graining-roll, and which thereby limits the quantity of lumber grained to what may be entered between the 5 rolls from one end of the machine. My roll, on the contrary, is originally a plain-surfaced metal roll, upon which the desired grain is sketched or imprinted and the surface of the roll not so marked cut away, leaving the grain 10 in full relief thereon, and using therewith double pressure-rolls movably supported above and below the fixed revolving graining-roll. I am thereby enabled to feed the machine from both ends of the same, the tables 15 being so arranged as to admit the lumber between the upper pressure and graining roll at one end of the machine and between the lower pressure and graining roll at the opposite end of the same, and the consequent doubling of 20 the product of the machine. I believe, therefore, that my mode of doing the same, and the rapidity with which it may be performed by the use of my improvement, is an advance in the art.

25 Having fully explained the construction and operation of my improved grainer, I desire to secure by Letters Patent the following claims thereon:

1. A wood-graining machine comprising

the following elements: frames having each 30 one central horizontal jaw and upper and lower vertical jaws, provided with suitable bearing-boxes, and caps with adjusting pressure-screws, a central graining-roll, and upper and lower pressure-rolls, suitable connecting and driving gear, with counter-shaft, pinion, and pulley thereon, substantially as shown, and for the purpose set forth. 35

2. In combination with a graining-machine frame, as described, the brackets D and tables 40 E, the central graining-roll, G, and pressure-rolls F F, gears H I J, shaft K, and pulley L, whereby the machine is made doubly operative, substantially as and for the purpose set forth. 45

3. In combination with a graining-machine frame, as described, the central graining-roll, G, constructed as described, movably fixed central to two equal-sized pressure-rolls placed vertically and adjustably, one on each side of 50 said central roll, connected by suitable gears, H, and arranged to be driven by gears I J, and pulley L on shaft K, substantially as and for the purpose specified.

EDWIN BRILLINGER.
